UNITED STATES PATENT OFFICE.

CHARLES J. MOSES, OF BOGOTA, NEW JERSEY.

TELEPHONE ATTACHMENT.

1,355,243.

Specification of Letters Patent. Patented Oct. 12, 1920.

Application filed May 15, 1917. Serial No. 168,780.

To all whom it may concern:

Be it known that I, CHARLES J. MOSES, a citizen of the United States, residing at Bogota, in the county of Hackensack, State 5 of New Jersey, have invented certain new and useful Improvements in Telephone Attachments; and I do hereby declare the following to be a full, clear, and exact description of the invention, such as will enable 10 others skilled in the art to which it appertains to make and use the same.

This invention relates to new and useful improvements in an attachment for telephone stands and has for its primary object 15 to provide a device by means of which suitable note paper may be secured to a telephone stand for use by the party using the telephone.

A further object of the invention is to 20 provide a device of this character in which a roll of paper may be supported in such a manner that the paper is capable of being fed across the paper supporting member.

A further object of the invention is to 25 provide a novel device for supporting a roll of paper.

Referring to the drawings,

Figure 1, is a perspective view of the device in place on a telephone stand,

30 Fig. 2, is a detail view of the arm, 2—2 of Fig. 1,

Fig. 3, is a detail plan view of the arm,

Fig. 4, is a detail plan view of the roll holder, and,

35 Fig. 5, is a sectional view on the line 5—5 of Fig. 1.

Referring more particularly to the drawings, the reference numeral 10 designates a suitable paper supporting table or plate 40 which is formed of a piece of metal and preferably rectangular in shape. One end of the table is provided with outwardly extending members which will be described more fully herebelow.

45 Across one end of the plate 10 is a strip 11 held thereon by means of fingers 12 formed from the central portion of the strip 11 and passed downward through slots in the plate 10 and then bent at an angle so 50 as to hold the strip 11 securely to the plate.

Arranged on one end of the strip 11 is 55 an adjustable bracket 15, the base of which is provided with a slot 13, through which the screw 14 passes and holds the bracket on the strip. It will be seen that this bracket can be adjusted on the strip 11, by

means of the screw 14, thus holding paper of different widths. The upper end of the bracket 15 is provided with an opening to receive one end of the paper-supporting 60 shaft 17.

The other end of the strip 11 has arranged thereon a hinged leaf 16 which is held against the paper roll by the spring 16'. The free end of the leaf 16 is provided with an elongated opening, to receive the other end of the shaft 17.

The other end of the plate 10 has arranged on its edges laterally extending ears 20 bent down as at 23 and provided with 70 openings 21. Overlying this end of the plate 10 is a guide 22, the ends of which have L-shaped ears to conform to the ears 20 on the plate 10, while its central portion is slightly curved and extends down past and 75 is spaced from the edge of the plate 10. The ears of the guide are provided with elongated openings through which pass screws taking into the downturned ends 23 of the ears 20 on the plate 10, so that the 80 guide 22 may be adjusted with respect to the plate.

The guide has its inner edge provided with two up-bent pencil holders 23' and an 85 upstanding thumb grip 24' so arranged that, when a slight outward and upward pressure is applied thereto, the inner edge of the guide will be raised sufficiently to permit the movement of the paper freely between it and the plate 10. When the pressure is released from the thumb grip 24' the 90 resiliency of its ears will pull the guide 22 back toward the plate 10, thus holding the paper at that end securely.

The numeral 30 designates an arm one 95 end of which is curved as at 31, and hinged to the end of the curved portion 31 is a clamp 33, the end of which is provided with a perforation through which a bolt 35 is adapted to pass to clamp the arm to the telephone stand. The opposite end of the arm 30 is provided with a fork 36 adapted to be secured to the under side of the writing table or plate 10 by means of rivets or the like, said means being so arranged as not to 100 interfere with the smooth surface of the plate 10.

From the foregoing description it will be seen that when a roll of paper is placed within the holder on the shaft 17, the paper 110 is prevented from accidental unwinding by the pressure of the leaf 16 against its end.

The free end of the paper is then slipped between the guide 22 and the plate 10, and the resiliency of the down turned ends 23 is sufficient to hold the paper on the writing surface. The user now smooths out the paper between the guide 22 and strip 10 and writing may be done upon its surface: thereafter pressure on the thumb grip 24 raises the guide as above stated, and the paper can be slipped along to the left to present a new surface as it is unwound from the roll.

Having thus described the invention, what is claimed, is:

- 15 1. A telephone attachment comprising a table, means for connecting it to a telephone, a paper clip at one end of the table, a strip lying across the other end of and having fingers engaged with slots in the table, a leaf connected by a spring hinge with one end of the strip, a right-angular bracket having in its upper end an opening

and in its base a slot, a set screw passing through said slot into strip, and a shaft carried by said leaf and engaging said opening, for the purpose set forth.

2. A telephone attachment comprising a table, means for connecting it to a telephone, paper-holding means at one end of the table, the other end having lateral ears provided with resilient downturned ends, and a paper clamping element whose body extends beyond this end of the table and has lateral ears turned down and connected with those mentioned whereby the body of the clamping element can be sprung upward off the table, for the purpose set forth.

In testimony whereof I affix my signature in the presence of two witnesses.

CHARLES J. MOSES.
